UNITED STATES PATENT OFFICE.

DELBERT U. McKEEN, OF TAMA, IOWA.

BARREL-COVER.

No. 888,029.

Specification of Letters Patent.

Patented May 19, 1908.

Application filed June 7, 1907. Serial No 377,757.

To all whom it may concern:

Be it known that I, DELBERT U. McKEEN, citizen of the United States, residing at Tama, in the county of Tama and State of Iowa, have invented certain new and useful Improvements in Barrel-Covers, of which the following is a specification.

The present invention relates to an improved closure for barrels or like receptacles 10 and aims to provide a novel form of cover which is so designed as to effectively protect the contents of the barrel from rain and dust.

The invention further contemplates the provision of a cover of this character which 15 can be cheaply formed of sheet material and which is sufficiently rigid to withstand any hard usage to which it may be subjected.

For a full description of the invention and the merits thereof and also to acquire a 20 knowledge of the details of construction and the means for effecting the result, reference is to be had to the following description and accompanying drawings, in which:

Figure 1 is a perspective view of a cover 25 embodying the invention. Fig. 2 is a transverse sectional view through the same. Fig. 3 is a similar view taken on a plane at right angles to that of Fig. 2. Fig. 4 is a detail view showing the construction of the shell.

30 Corresponding and like parts are referred to in the following description and indicated in all the views of the drawings by the same reference characters.

Specifically describing the invention, the 35 numeral 1 designates the body portion of the cover which is of a shape corresponding to that of the receptacle in connection with which the cover is to be employed, and in the present instance is shown as circular. An 40 annular rim 2 projects laterally from the periphery of the body portion 1 and forms a means for engaging the top or upper portion of the barrel or other receptacle. A pair of oppositely extending tongues 3 stamped 45 from the central portion of the top or body portion 1 of the cover and coöperate with each other and the portion of the cover between the same are bent rearwardly to form the handle 4 which is hollow and constitutes 50 a convenient means for manipulating the cover.

In the preferred embodiment of the invention as shown in the drawings the tongues 3 are formed by approximately semi-circular 55 cuts in the top 1 of the cover and when bent rearwardly leave a pair of approximately

semi-circular openings in the top of the cover. In order to prevent rain or dust from reaching the interior of the barrel or receptacle through these openings, a shell 5 is applied to 60 the lower face of the top 1 of the cover. This shell has a dished formation so as to receive the handle 4 and has the edge portions thereof soldered or otherwise connected to the cover so as to prevent rain or dust from obtaining access to the receptacle. In the present instance this shell 5 is formed from a piece of sheet material having a pair of incisions 6 formed in opposite sides thereof, the edges of the incisions being overlapped 65 to impart a dished or concave formation to the shell. It may also be noted that the shell 5 serves as a reinforcing means for the cover and enables the same to withstand a considerable amount of weight without bending or being in any manner injured. This manner of constructing the cover also has the advantage of providing a plain upper face which is free from all projections and therefore permits boxes or like members to 70 obtain a firm seat upon the cover.

Having thus described the invention, what is claimed as new is:

1. A cover of the character described, formed of sheet material and having a pair of 85 oppositely extending tongues stamped therefrom, the said tongues being bent rearwardly and coöperating with each other and the portion of the cover between the same to form a handle for manipulating the cover. 90

2. A cover of the character described comprising a body portion having openings formed therein, and a shell applied to the body portion and formed of a plate provided in its sides with incisions the edges of which 95 are overlapped to impart a concave formation to the plate.

3. A cover of the character described comprising a body portion having approximately semi-circular tongues stamped from opposite 100 sides thereof and bent rearwardly to form a handle, and a shell applied to the inner face of the body portion of the cover and having a concave formation to receive the rearwardly bent tongues forming the handle. 105

In testimony whereof I affix my signature in presence of two witnesses.

DELBERT U. McKEEN. [L. S.]
